WIRE BRUSH HOLDER

Filed March 9, 1944

Inventor:
FLOYD FOGLIASSO,

Floyd Fogliasso
Attorney.

UNITED STATES PATENT OFFICE

2,392,909

WIRE BRUSH HOLDER

Floyd Fogliasso, Arlington, Calif.

Application March 9, 1944, Serial No. 525,643

7 Claims. (Cl. 15—180)

My invention relates to brushes, and relates in particular to a simple brush which may be power driven and which is capable of hard usage.

It is an object of the invention to provide a brush which may be attached to the end of a rotary member, such as a motor driven shaft, and which is adapted for cleaning surfaces of different types of material in an efficient and economical manner. For example, one form of my invention is especially adapted for cleaning the surfaces of metal tanks and for cleaning slag and metallic oxides from the surfaces of welded joints. It will be understood that the character of the material forming the surface to be cleaned or brushed will determine the character of material employed in the strands forming the brush elements of the brush assembly. For cleaning of slag and other substances from steel surfaces, the brush elements of my invention are made from durable and relatively thin steel wire, but other uses of the invention may require that the brush elements be made from soft wire, such as copper or brass, or from other soft material.

It is an object of the invention to provide a brush assembly having simple brush elements which may be readily replaced by the workman. It is found that the severe usage imposed upon brushes of this type results in a relatively rapid wearing away of the strands, for example, wires, from which the brush is formed, the result being that the expense of replacing complete brushes becomes relatively large. In the use of my invention, the complete brush is not replaced when the brush becomes worn, but in a simple manner the workman may quickly replace worn brush elements in the hub or holder portion of the brush which is substantially indestructible in ordinary use.

It is a further object of the invention to provide a brush assembly having a body with means for attaching it to a rotatable shaft, this body having at its forward end a recess and having a pin or core therein to form in the recess an annular chamber to receive the rear ends of a plurality of brush elements of simple form, there being means operative within the recess to securely lock the brush elements in place.

A further object of the invention is to provide a brush holder of the character indicated in the foregoing paragraph having a core member which is provided with radial projections to engage the inner ends of the brush elements and hold these brush elements securely within the body until the core is removed at a time when it is desired

to replace worn brush elements with new brush elements.

A further object of the invention is to provide a simple form of brush element comprising a bundle of strands, this bundle of strands being bent intermediate its ends so that the two halves of the bundle lie in adjacent relation, the bent portion at the rearward end of the bundle forming a loop adapted to be engaged by means for securing the brush element in the holder for which it is intended.

Further objects and advantages of the invention will be brought out in the following part of the specification.

15 Referring to the drawing which is for illustrative purposes only,

Fig. 1 is a side elevation of a power driven brush device embodying my invention.

Fig. 2 is an enlarged sectional view of the brush assembly shown in Fig. 1.

Fig. 3 is a perspective view showing the component elements of the brush assembly separated, for the purpose of illustrating the ease with which these parts are assembled.

25 The brushing device 5 shown in Fig. 1 consists of a portable motor 6 having a suitable handle 7 and having means 8 whereby power may be delivered to the motor 6. At the forward end of the motor there is a driven shaft 9 which supports the brush assembly 10, this brush assembly 10 comprising a plurality of brush units 11 which project forwardly from a holder body 12.

As shown in Fig. 2, the holder body 12 has a recess 13 at its forward end, and from its rearward end there extends an externally threaded projection 14 which screws into the internal threads 15 at the forward end of a connector 16 which also has internal threads 17 at its rearward end whereby the connector may be screwed onto

35 the shaft 9 of the motor device 6. The holder body 12 has an axial opening 18 which extends from the bottom of the recess 13 to the rear face of the projection 14, and a pin or core 19 is removably disposed within the body 12. This core

40 has a forward portion 20, the front end 21 of which lies ahead of or outside of the recess 13 and is expanded or enlarged so as to form at the front end of the core 19 a conical head. The core also has a rearward portion 22 which extends through the axial opening 18 and has threads 23 to receive a nut 24 which occupies a position in the cavity of the connector 16 when all of the parts are assembled as shown in Fig. 2.

45 The wall of core 19 is provided with radially extending protrusions, or fingers 25, which fin-

gers 25 are preferably in the form of flattened pins. In the form of the invention shown, there are four of the members 25 and each of these members 25 has a rearwardly faced shoulder 26 which is spaced from the bottom wall 27 of the recess 13.

Each of the brush elements 11 is made from a plurality of strands 30. These strands are selected in accordance with the service for which the brush is intended. They may be wires of square, flat, or round cross section. For general scouring and cleaning of iron or steel parts or wall surfaces, the strands 30 are made from tempered steel wire. Each brush element 11 is formed by taking a bundle of these strands 30 cut to a length substantially twice the length of the brush element 11. The bundle of strands 30 is then bent intermediate the ends thereof, substantially at the center of the bundle, and one half of the bundle of strands is bent back so as to lie adjacent the other half of the bundle, and the strands of the two halves of the bundle are then twisted as shown at 31 in Fig. 2, and also in Fig. 3. The bending of the bundle of strands 30 forms at the rear end of the brush element 11 a loop 32 defining an opening 33 through which one of the members 25 may project. The brush elements 11 are of such size with relation to the holder body 12 and the forward portion 20 of the core 19 as to substantially extend across the occupied portion of the annular space 35 within the body 12 externally of the forward portion 20 of the core 19.

When it is desired to assemble the brush elements 11 in the holder body 12, the parts of the brush assembly are disassembled as shown in Fig. 3. The brush elements 11 are then assembled around the forward portion 20 of the core 19 in such positions that the protrusions 25 will project through the openings 33 of the loops 32. The holder body 12 is then moved forwardly over this assemblage of core and brush elements 11 so that the outer wall of the body 12 will enclose the rearward ends of the brush elements 11 and so that the rearward portion 22 of the core 19 will extend back through the axial opening 18 of the body 12. The nut 24 is then applied and then screwed up relatively tight so as to securely clamp the brush elements 11 in place in the holder body 12 as shown in Fig. 2. The connector 16 is then screwed onto the projection 14, and the brush assembly is ready for use on the shaft 9 of the motor 6. When the brush assembly 10 is rotated at relatively high speed, the front ends of the strands 11 will be swung outward by centrifugal force from the positions in which they are shown, and by suitable maneuvering of the entire assemblage 5 shown in Fig. 1, the strands 30 may be brought into positions to engage the surface to be brushed or scoured.

It will be understood that even though the strands 30 are made of durable steel wire, they may wear down quite short in a relatively small time. The workman may readily replace the worn brush elements 11 by disassembling the parts as shown in Fig. 3 and reforming the assembly with new brush elements as clearly indicated in the foregoing explanation.

I claim as my invention:

1. In a brush assembly of the character described; for attachment to the end of a rotating shaft, the combination of: a connector having means at its rear end for connecting it to said shaft and having an internally threaded cavity at its forward end; a holder body having a recess

at its forward end and a threaded projection at its rearward end which screws into said cavity of said connector, there being an axial opening leading from said recess to the rear face of said projection; a plurality of brush elements, each consisting of a bundle of strands bent intermediate the ends thereof so that the halves of the strands will lie in adjacent relation, said halves of said strands being also twisted helically together so that a loop is formed at the rear end of said brush element; a core extending axially within said body and defining an annular space in said recess of said body to receive the rearward ends of said brush elements, said core being enlarged at its forward end and having its rearward end extending through said axial opening of said body, said core having radially extending protrusions to engage said loops at the rear ends of said brush elements; and nut means threaded on the rearward extremities of said core to hold said core in said body.

2. In a brush holder of the character described, for attachment to the end of a rotating shaft, the combination of: a connector having means 25 at its rear end for connecting it to said shaft and having an internally threaded cavity at its forward end; a holder body having a recess at its forward end and a threaded projection at its rearward end which screws into said cavity of said connector, there being an axial opening leading from said recess to the rear face of said projection; a core extending axially within said body and defining an annular space in said recess of said body to receive the rearward ends of said brush elements, said core being enlarged at its forward end and having its rearward end extending through said axial opening of said body, said core having radially extending protrusions to engage said loops at the rear ends of said brush elements; and nut means threaded on the rearward extremities of said core to hold said core in said body.

3. In a brush holder of the character described, for attachment to the end of a rotating shaft, the combination of: a holder body having a recess at its forward end and being adapted to be connected to a rotating member; a core extending axially within said body and defining an annular space in said recess of said body to receive the rearward ends of said brush elements, said core being enlarged at its forward end and having radially extending protrusions provided with rearwardly faced shoulders which are spaced from the bottom of said recess; and nut means threaded on the rearward extremities of said core to hold said core in said body.

4. In a brush assembly of the character described, for attachment to the end of a rotating shaft, the combination of: a holder body having a recess at its forward end and being adapted to be connected to a rotating member; a plurality of brush elements, each consisting of a bundle of strands bent intermediate the ends thereof so that the halves of the strands will lie in adjacent relation, said halves of said strands being also twisted helically together so that a loop is formed at the rear end of said brush element; a core extending axially within said body and defining an annular space in said recess of said body to receive the rearward ends of said brush elements, said core being enlarged at its forward end and having radially extending protrusions to engage said loops at the rear ends of said brush elements; and means for locking said core in said body.

5. In a brush assembly of the character described, for attachment to the end of a rotating

shaft, the combination of: a holder body having a recess at its forward end and being adapted to be connected to a rotating member; a plurality of brush elements, each consisting of a plurality of strands and each having an opening at its rearward end; a core extending axially within said body and defining an annular space in said recess of said body to receive the rearward ends of said brush elements, said core being enlarged at its forward end and having radially extending protrusions to engage said openings at the rear ends of said brush elements; and means for locking said core in said body.

6. In a brush assembly of the character described, for attachment to the end of a rotating shaft, the combination of: a connector having means at its rear end for connecting it to said shaft and having an internally threaded cavity at its forward end; a holder body having a recess at its forward end and a threaded projection at its rearward end which screws into said cavity of said connector, there being an axial opening leading from said recess to the rear face of said projection; a plurality of brush elements, each consisting of a plurality of strands and each having an opening at its rearward end; a core extending axially within said body and defining an annular space in said recess of said body to receive the rearward ends of said brush elements, said core being enlarged at its forward end and having its rearward end extending through said axial opening of said body, said core having radially extend-

ing protrusions to engage said openings at the rear ends of said brush elements; and nut means threaded on the rearward extremities of said core to hold said core in said body.

5 7. In a brush assembly of the character described, for attachment to the end of a rotating shaft, the combination of: a connector having means at its rear end for connecting it to said shaft and having an internally threaded cavity at its forward end; a holder body having a recess at its forward end and a threaded projection at its rearward end which screws into said cavity of said connector, there being an axial opening leading from said recess to the rear face of said projection; a plurality of brush elements, each consisting of a bundle of strands bent intermediate the ends thereof so that the halves of the strands will lie in adjacent relation, said halves of said strands being also twisted helically together so that a loop is formed at the rear end of said brush element; a core extending axially within said body and defining an annular space in said recess of said body to receive the rearward ends of said brush elements, said core having its rearward end extending through said axial opening of said body, said core having radially extending protrusions to engage said loops at the rear ends of said brush elements; and nut means threaded on the rearward extremities of said core to hold said core in said body.

FLOYD FOGLIASSO.
